UNITED STATES PATENT OFFICE.

JAMES E. BRADY, OF NEW YORK, N. Y.

STUD.

1,425,507.

Specification of Letters Patent. Patented Aug. 15, 1922.

Application filed July 30, 1920. Serial No. 400,196.

To all whom it may concern:

Be it known that I, JAMES E. BRADY, a citizen of the United States, residing in New York city, county of New York, borough 5 of Manhattan, and State of New York, have invented certain new and useful Improvements in Studs, of which the following is a full, clear, and exact specification.

My invention relates to building studs and 10 refers particularly to studs useful in the construction of partitions.

Partitions, composed of plaster, cement or similar materials, may be classified into 15 solid partitions and hollow partitions, and the stud of my invention is suitable in the construction of both of these forms of partitions.

The object of my device is a cheap, light, 20 efficient partition stud, readily applied to partition construction with a minimum amount of time and labor.

In the production of partitions of the character described, it has been previously 25 customary to erect a series of vertical studs 25 of wood or metal which were fastened to the floor joist and ceiling joist by means of nails or bolts. To these studs were nailed, or otherwise fastened, a series of lath, plaster-board or other foundation material as a 30 base for the final layer of plaster or cement.

The production of partitions in the manner described has many difficulties and objectionable features. The large amount of 35 wood has a tendency to make the partition non-fireproof, metal studs are expensive and heavy, a very considerable amount of labor is required to position the studs and the remainder of the base elements and continual 40 plumbing is necessary to insure a properly aligned structure.

Hollow tiles, or bricks, have been employed for the production of hollow partitions, but these have the objection of high 45 cost, the necessity of a great amount of labor incident to their proper laying, and the difficulty incident to the proper alignment of the partition surface or face.

My device overcomes all of these objections 50 and difficulties and presents a means whereby fire-proof partitions of either solid or hollow formation may be effectively constructed with a minimum of weight, time and labor.

I have found that a stud of double con-

cavo-convex formation possesses valuable ad- 55 vantages not found in other forms of studs, in that it possesses sufficient strength and stability even if made of heavy cardboard.

I have further found that a stud of this formation possesses other advantages in that 60 it allows of the speedy production of partitions which, on account of the uniform body of cement, plaster or other material employed, is fire-proof, the plaster, or other material, forming a unified body of fire-re- 65 sistant material and of great stability irrespective of the stud.

Among the other advantages of my device is its adaptability to the production of both 70 solid and hollow partitions, whether produced from wood lath, metal lath, fabric, plaster-board or any other materials capable of being used for this purpose.

The device of my invention comprises two 75 connected concavo-convex bodies attached to each other with their concave faces exposed outwardly.

In the accompanying drawings and description thereof, I refer to a paper stud, but I do not limit myself to this particular 80 substance, paper being mentioned in order to show that even this cheap, light material may be used to produce a firm, permanent fire-proof partition, and that my device requires a minimum of time in that the produc- 85 tion of a partition therewith eliminates all the labor incident to nailing, screwing or bolting together the various members.

In the accompanying drawings, illustrating 90 modifications of the device of my invention, similar parts are designated by similar numerals.

Figure 1 is a broken vertical section showing a series of my devices in the construction of a partition using plaster-board. 95

Figure 2 is a section through the line 2—2 of Figure 3.

Figure 3 is a broken side elevation of my device looking in the direction of one of its 100 concave faces.

Figure 4 is a section through the line 4—4 of Figure 1.

Figure 5 is a section through the line 5—5 of Figure 1.

Figure 6 is a broken horizontal section 105 showing my device in the construction of a hollow partition, employing plaster-board.

Figure 7 is partly a horizontal section and

partly a top plan view showing my device in the construction of a solid partition, employing a fabric.

Figure 8 is a broken side elevation of Figure 7, with the plaster removed.

Figure 9 is a broken horizontal section of my device showing its employment with fabric for the production of a hollow partition.

Figure 10 is a horizontal section of a modified form of my device.

The particular form of the device of my invention, shown in the accompanying drawings, comprises a heavy paper, or card-board, stud formed by two concavo-convex members 10, 10, connected with their convex faces abutting each other by means of a series of fastening means 11, 11. The concave faces carry a series of extended guide members 12, 12, for purposes to be described later, and the members 10, 10 have a series of holes, or openings 13, 13. The members 10, 10 carry an extended foot, or support, 14, preferable of wire screening, a similar support, not shown, being carried by the upper extremities of the members 10, 10.

Figures 1, 2, 3, 4 and 5 illustrate the use of my device in the production of a partition with the use of plaster-board, the means of employment being as follows:

A series of the connected concavo-convex members 10, 10 are placed in spaced position with their concave faces toward each other and are maintained in position by fixing the supports 14, 14 to the floor and ceiling joist by means of plaster or cement. The connected concavo-convex members are so spaced from each other that plaster-board may be situated between them and maintained in position by means of the guides 12, 12. A coating of plaster is placed upon the concave faces of the studs and a plaster-board 15 is placed between the guides 12, 12 of the adjacent studs. A spacing clip 16 is then placed around each member of the studs and another plaster-board inserted, the clip 16 spacing the two plaster-boards from each other. This process is followed until a plaster-board partition is formed supported by the studs. Plaster 17 is now placed over the entire structure, including the plaster-boards and the studs. During this plastering operation, the plaster goes through the holes 13, 13 of the studs and between the spaces between the plaster-boards, thus forming a concrete unified structure of plaster, in which the studs are imbedded, the whole being of such a formation as to form a fire-proof partition.

Figure 6 discloses a method of making hollow fire-proof partitions by means of the device of my invention. In this particular form of construction, the studs are erected in the manner described above and carry the two plaster-boards 15, 15 which are spacedly

connected with each other by the concrete, or plaster, members 18, 18, through which a wire 19 passes and is turned over upon the outer faces of the plaster-boards as a connecting and binding means. The series of 70 plaster-boards are separated from each other by the spacing clips 16, 16, as described above, and the entire structure covered with plaster to form the partition.

Figures 7 and 8 illustrate a method of 75 producing a solid partition by means of my device employing a textile fabric as open-work burlap. In this modification, the proper length of fabric 20, necessary for the production of the partition, is fastened 80 between a series of the concavo-convex members at proper distances from each other by means of a clip 21 which binds together the burlap and the two elements 10, 10. It is to be noted that in this form of construction 85 the concave faces of the stud face outwardly. Plaster 17 is then placed over the entire structure, forming a solid fire-proof partition.

Figure 9 illustrates a method of producing 90 a hollow partition by means of my device employing a fabric. In this modification the fabric 20 is attached at intervals to a series of studs, a layer of fabric being so attached to the concave face of each member 95 10 of the stud. The entire structure is then covered with plaster, forming a hollow fire-proof partition.

In the modification of my device, shown in Figure 10, the two members 10, 10 are 100 connected together, but spaced from each other by means of the cement, or plaster, member 22, through which the wire 23 passes and is turned over the concave face of each member 10, as a holding and binding member. Each stud carries a series of 105 such members 22. The object of this modification is to allow of the formation of a thicker partition than could be formed if the members 10, 10 abutted upon each other. 110

The utility, strength, effectiveness, novelty, ease of erection and economy of cost of my device are illustrated by the foregoing description of it and its several methods of use.

I do not limit myself to the exact size, shape, number, material or arrangement of parts as shown and described, all of which may be varied without going beyond the scope of my invention as shown, described 120 and claimed.

What I claim is:—

1. In a building stud, in combination, two concavo-convex members having their concave faces oppositely directed, a series of 125 openings within said members, and screen means carried by the extremities of said members for maintaining the studs in vertical position.

2. In a building stud, in combination, two 130

concavo-convex members having their concave faces oppositely directed, a series of openings within said members, a series of outwardly extended guides carried by the concave faces of said members capable of receiving and maintaining plaster boards, a series of spacing members carried by the concavo-convex members capable of allowing a space between plaster boards carried thereby and screen means carried by the extremities of the concavo-convex members for maintaining the studs in vertical position. Signed at New York city in the county of New York and State of New York this 28th day of July, 1920.

JAMES E. BRADY.
